UNITED STATES PATENT OFFICE.

DEVILLO J. NICHOLS AND WILLIAM H. SHEPARD, OF THREE RIVERS,
MICHIGAN.

SLIPPERY-ELM TENT.

SPECIFICATION forming part of Letters Patent No. 375,185, dated December 20, 1887.

Application filed February 19, 1887. Serial No. 228,272. (No model.)

To all whom it may concern:

Be it known that we, DEVILLO J. NICHOLS and WILLIAM H. SHEPARD, citizens of the United States, residing at Three Rivers, in the county of St. Joseph and State of Michigan, have invented certain new and useful Improvements in Bougies; and we do hereby declare the following to be a full, clear, and exact description of the invention, such as will enable others skilled in the art to which it appertains to make and use the same.

Our invention relates to tents or bougies, which are used in the practice of medicine.

On account of the valuable medicinal properties of the inner lining of slippery-elm bark, this substance has been used for tents or bougies; and the prevailing custom has been to cut them out of pieces of bark of various thicknesses into sizes suitable for application, 2c those of large diameter from thick pieces of bark and those of smaller diameter from thinner pieces. But this process is long and tedious and far from satisfactory, because the tents or bougies thus made in one piece vary 25 in quality, as those made from thick bark have a much coarser fiber and are less susceptible to moisture than those made from the thinnest and best portion of the bark.

The object of our invention is to manufacture these slippery-elm tents or bougies not only in a much more rapid and economical manner, but so that the quality will be uniform regardless of their length or thickness; and to this end our invention consists in the 35 product more fully described hereinafter, and pointed out in the claims.

In the accompanying drawings, Figure 1 represents several strips of slippery-elm bark placed together prior to being compressed; 40 Fig. 2, the strips or layers after they have been compressed into a solid mass, and Fig. 3 a completed bougie or tent made from the mass or blank after it has become hardened by drying.

45 In putting our invention into practice several pieces, *a*, of slippery-elm bark are moistened and placed one upon or alongside the other, so that the grain or fiber of the bark

will have a common direction, and they are then subjected to a high degree of pressure. 50 The natural gummy substance in the bark will make the layers or strips so strongly adhere that when the pressure is released a solid blank or mass is formed, and from this mass or block the tents or bougies are afterward cut 55 out into various shapes and sizes, the form shown in Fig. 3 being preferred, the lines *b* in this figure representing the junctions of the several layers.

The thick bougies now in use are made in 60 one piece out of a single piece of bark, and therefore have such a coarse and woody fiber that they are slow in absorbing moisture and require a longer time to become moistened and flexible after being inserted in the patient 65 than those made from the thinner fine-grained pieces.

By our method we select strips of that part of the bark which has the finest fiber and press them together into a solid blank, and 70 afterward cut or turn therefrom bougies of a large diameter which will have as fine a texture and possess all the good qualities of the smallest and best bougies formerly made of a single piece of bark.

Having thus fully described our invention, what we claim, and desire to secure by Letters Patent, is—

1. As a new article of manufacture, a tent or bougie formed of layers or strips of slippery-elm bark compressed together in solidified form, substantially as described.

2. As a new article of manufacture, a tent or bougie formed of layers or strips of slippery-elm bark compressed together in solidified form, the grain of the several layers running in the same direction, substantially as described.

In testimony whereof we affix our signatures in presence of two witnesses.

DEVILLO J. NICHOLS.
WILLIAM H. SHEPARD.
